[57] CLAIM

The ornamental design for a gas-fired heating stove, as shown and described.

[21] Appl. No.: 6,800

DESCRIPTION

[22] Filed: Apr. 7, 1993

FIG. 1 is a front elevation view of a gas-fired heating stove embodying the subject invention;
FIG. 2 is a first side elevation view thereof, the opposite side elevation view being a mirror image thereof;
FIG. 3 is a top plan view thereof;
FIG. 4 is a bottom plan view thereof; and,
FIG. 5 is a rear elevation view thereof.
